UNITED STATES PATENT OFFICE

2,185,826

ROTATABLE ANODE X-RAY TUBE

Zed J. Atlee, Chicago, Ill., assignor to General
Electric X-Ray Corporation, a corporation of
New York

Application June 7, 1938, Serial No. 212,268

4 Claims. (Cl. 250—93)

The present invention relates to improvements in X-ray apparatus of the type which includes an X-ray tube having a stationary electrode and a relatively rotatable electrode.

It is an advantage of X-ray tubes of this character that they are able to operate with very high discharge currents. However, the safe use of such currents depends upon the maintenance of a definite speed of rotation of the relatively movable electrode. To employ the full operating current with the movable electrode stationary or rotating at reduced speed may result in serious damage to the X-ray target.

It is an object of my present invention to provide means for automatically preventing the supply of normal discharge current to a rotating element X-ray tube unless and until the said element is revolving at its intended speed.

The features of novelty which I desire to protect herein are pointed out with particularity in the appended claims. The invention itself together with further objects and advantages thereof may best be understood by reference to the following description taken in connection with the drawing in which Fig. 1 illustrates diagrammatically an X-ray apparatus suitably embodying the invention and Fig. 2 is a graphical representation useful in explaining the invention.

Referring particularly to Fig. 1, I have shown an X-ray tube of the type described in application Serial No. 78,996, filed May 11, 1936, in the names of Malvern J. Gross and Zed J. Atlee. This comprises a sealed evacuated envelope 10 enclosing a separately heated cathode, shown in outline at 11, and a rotatable anode 12 having thereon an inclined peripheral target face 13. The anode 12 is intended to be rotated during normal operation and is mechanically connected to a driving means comprising an induction rotor 14. The rotor may comprise a squirrel cage construction such as is described and claimed in the application Serial No. 78,996 above referred to. In order to supply driving force to the rotor 14 there is provided an electromagnetic stator which is outside the discharge envelope and which is indicated diagrammatically in dotted outline at 15. The stator is provided with polyphase windings 16 and 17 (shown separately for clarity) whose character and mode of energization will be set forth more fully hereinafter.

The energizing means for the various instrumentalities is shown as comprising a common power source 18 which is connected to an auto-transformer 19 through a manually operable

switch 21. The auto-transformer is provided with a plurality of terminals which make it possible to derive a number of different potentials from the same voltage source.

One set of these terminals, namely, terminals 23 and 24, are used for supplying heating current to the cathode 11 through the intermediate of a transformer 25. Regulation of the heating current is accomplished by means of a variable resistor 26 connected in series with the transformer primary.

The main discharge current for the X-ray tube is provided by means of a transformer 27 which has its primary connected between terminals 23 and 28 of the auto-transformer 19. The energizing circuit thus provided is controlled jointly by a manually operable switch 29 and by a solenoid operated relay 30, the operation of which will be more fully explained hereinafter.

Referring again to the windings 16 and 17 of the stator 15, it should be pointed out that these are of such character as to provide a rotating magnetic field when supplied with polyphase currents. In order to obtain such currents from the single phase source 18, a phase-splitting device is employed in the form of a condenser 32. In operation, the potential which exists between terminals 23 and 35 of the auto-transformer 19 is applied directly to the stator winding 16 by means of conductors 36 and 37. It is applied indirectly to the winding 17 through these same conductors connected in series with the condenser 32. The action of this condenser is to produce a phase difference between the currents flowing in the two windings so as to obtain the effect of polyphase excitation of the stator. By this means a rotating magnetic field is produced which is effective to exert a strong torque on the rotor 14 and to rotate it and the connected anode 12.

Rotation of the anode 12 during use causes the heating effect of the discharge current passing between it and the cathode 11 to be distributed over the entire target surface 13 and obviates the danger of localised burning. The amount of discharge current which can be safely handled is a function of the speed of rotation and may be very high under proper conditions. However, the use of extremely high currents involves the danger that a decrease in speed below the intended value may result in destructive overheating of the target. Such a decrease in speed may be caused, for example, by total or partial failure of the power supply of the driving system or by a defective condition of the

bearings on which the rotating parts are supported.

In accordance with my present invention, means is provided for assuring that the discharge circuit shall be fully energized only when the rotor 14 is turning at its normal speed or at a speed not materially below normal. To this end there is provided in connection with the stator energizing circuit, means effective to control 10 the operation of the relay 30 in such a manner as to accomplish the desired result. This means comprises a device which is responsive to an electrical condition of the stator energizing circuit, specifically a solenoid operated relay 39 15 which is controlled by variations in voltage across the stator winding 17. The particular control arrangement shown includes a condenser 41 and a pair of resistors 42 and 43 connected in series across the stator winding 17. The energizing 20 coil of the relay 39 is connected across the condenser so that the relay is maintained in its closed position when and as long as the voltage of the condenser 41 is in excess of a predetermined minimum value. 25 It will be observed that actuation of the relay opens the upper contacts 48, 49 of the relay and places the resistor 42 in circuit with the winding 17. This makes the relay more sensitive to a slight drop in voltage. The condenser 41 30 has the effect of preventing chattering action of the relay.

The action of the control circuit just described may be understood by referring to Fig. 2 which shows the relationship which exists between the 35 voltage appearing across the stator winding 17 and the speed of the rotor 14. The variation of voltage is due to changes in the apparent impedance of the winding which are produced by the varying reaction of the rotor currents on the 40 stator windings at different speeds. At some point on the curve, such as that indicated at A, the voltage appearing across the winding 17 and more specifically that portion of it which appears across the condenser 41 will be great enough to cause the relay 39 to close. If, at some later 45 time, the speed of the rotor again drops, say, to the point B, the relay 39 will reopen.

Closure of the relay 39 serves to complete the 50 energizing circuit for the relay 30—at least insofar as this circuit depends upon the existence of a connection between relay terminals 46 and 47. (The relay 30 is under the joint control of the relay 39 and of an exposure-timing device 50). The complete relay circuit may be traced 55 from terminal 51 of the auto-transformer 19 through the coil of relay 30, timer 50, conductor 52, relay contacts 46 and 47, and conductor 53 back to terminal 23 of the auto-transformer.

Assuming that the timer 50 is in its closed position, closure of the relay 39 will permit the 60 supply of discharge current to the X-ray tube. Furthermore, subject to the operation of the timer 50, such discharge current may be continued as long as the speed of the rotor 14 remains above the predetermined minimum. If, for any reason 65 this speed drops below such minimum, the relay 39 will open so as to prevent further flow of discharge current and consequent damage to the X-ray target. The operation of the relay 39 may 70 be adjusted to provide for its closure at different speeds of the rotor 14 or its use at different voltages by varying the values of the resistors 42 and 43. It will be understood that as the value 75 of the resistors is decreased the proportion of the total voltage which appears across the condenser

41 will increase. Consequently the relay will remain closed for lower speeds than would be the case with higher resistor values.

It is not necessary that the relay 39 operate to 5 interrupt the supply of discharge current completely. It would be a sufficient protection, for example, if its operation were to introduce into the discharge circuit an impedance of such magnitude as to reduce the current flow to a safe 10 value.

It will further be understood that the particular circuit which I have illustrated is in no way 15 essential to the purposes of the invention. Various changes may be made by those skilled in the art and I aim in the appended claims to cover all such equivalent modifications as fall 20 within the true spirit of the foregoing disclosure.

What I claim as new and desire to secure by Letters Patent of the United States is:

1. In an apparatus of the type which includes 25 a discharge tube having a stationary electrode, a rotatable electrode and electromagnetic means for driving the rotatable electrode, the combination which comprises a first electrical circuit for supplying operating current to the said tube, a second electrical circuit for energizing the said 30 electrode driving means, the electrical conditions of said second circuit being variable in accordance with variations in the speed of rotation of said electrode, and means associated with said second circuit and responsive to an electrical condition thereof for preventing the supply of normal 35 operating current to the tube except upon the attainment of a desired speed of rotation of the said rotatable electrode.

2. In an apparatus of the type which includes 40 an X-ray tube having a stationary cathode, a rotatable anode, an electromagnetic rotor mechanically connected to the anode and an electromagnetic stator for supplying driving force 45 to the rotor, the combination which comprises a first electrical circuit for supplying discharge current to the tube, a second electrical circuit for supplying energizing current to the stator, the electrical conditions of said second circuit being variable in accordance with variations in the speed of rotation of said rotor, and means 50 associated with said second circuit and responsive to an electrical condition thereof for preventing the completion of the said discharge current circuit except upon the attainment of a desired speed of rotation of the rotor.

3. In an apparatus of the type which includes 55 an X-ray tube having a cathode, a rotatable anode, an electromagnetic rotor mechanically 60 connected to the anode, and an electromagnetic stator for supplying driving force to the rotor, the combination which comprises a first electrical circuit for supplying discharge current to the tube, a second electrical circuit including energizing windings for the stator, at least certain 65 of said windings being of such character that the voltage drop therethrough varies materially in response to variations in the speed of rotation of the rotor and means responsive to such variations in voltage drop for preventing completion of the said first circuit except upon the existence of a predetermined speed of rotation of the rotor.

4. An X-ray apparatus including an X-ray tube 70 having a stationary cathode and a rotatable anode, an electrical circuit for supplying discharge current to the tube, an induction rotor connected with the anode for driving the same, an electromagnetic stator having a pair of polyphase windings for supplying driving force to the rotor, a 75

source of single phase potential adapted to be connected directly to one of said windings and indirectly to the second winding through a phase shifting device, a relay for controlling the said discharge current circuit, and means responsive to the potential drop across the said second stator

winding for controlling the operation of the relay, whereby the supply of normal discharge current to the tube is made dependent on the attainment of a desired operating condition of the rotor.
